UNITED STATES PATENT OFFICE.

FRANZ BURGER AND HENRY M. WILLIAMS, OF FORT WAYNE, INDIANA;
SAID BURGER ASSIGNOR OF ONE-FOURTH TO SAID WILLIAMS.

WINDOW-VENTILATOR.

SPECIFICATION forming part of Letters Patent No. 613,354, dated November 1, 1898.

Application filed August 7, 1897. Serial No. 647,451. (No model.)

To all whom it may concern:

Be it known that we, FRANZ BURGER and HENRY M. WILLIAMS, citizens of the United States, residing at Fort Wayne, in the county 5 of Allen and State of Indiana, have invented certain new and useful Improvements in Ventilators, of which the following is a specification.

This invention relates to certain new and 10 useful improvements in ventilating apparatus for buildings and conveyances of all kinds. It is more particularly adapted, however, for use in connection with street and railway cars, having for its object to provide 15 simple and efficient means whereby fresh air is introduced into the car and the vitiated air discharged therefrom.

With this object in view the invention consists in the novel construction, combination, 20 and arrangement of the parts hereinafter more particularly described.

In the accompanying drawings, forming a part of the specification, and in which like letters and figures of reference indicate corresponding parts, Figure 1 is a sectional view of 25 a portion of a window and its frame with the ventilator applied thereto. Fig. 2 is a horizontal sectional view on the line *x x*. Fig. 3 is a vertical sectional view on the line *y y*, looking in the direction of the arrow, Fig. 1.

Referring more particularly to the drawings, A designates the ventilator, which may be secured in the side wall of a car or building; but preferably it is arranged, as shown, 35 in the lower bar of a window-sash 1. This sash-bar is provided with an opening extending entirely through it, and into this opening is fitted a metallic thimble 2. Within the thimble 2 is fitted to move longitudinally a 40 sleeve 3, having its outer end open and provided with an inner closed end formed with a head 4, and near said inner end the sleeve is formed with lateral openings 5.

Secured to the inner face of the sash-bar 45 is a semicircular casing 6, having its lower end open to permit ready access to the inner headed end of the sleeve 3, which is partially inclosed by the casing. The vertical wall of this casing serves as a stop for limiting the 50 withdrawal of the sleeve 3 from the thimble 2, and upon the inside face of the wall is

formed a segmental bearing 7, against which the upper edge of the head 4 rests in contact when the sleeve is fully withdrawn from the thimble.

The casing 6, in addition to serving as a shield for the sleeve 3, also serves as a finger-piece by means of which the window may be lifted, and if this is effected while the sleeve 3 is withdrawn from the thimble 2 the bending of the sleeve will be prevented by the segmental bearing 7, with which its head is in contact.

Upon the outer face of the sash-bar is a second casing 8, which partially incloses the 65 outer end of the sleeve 3 and has its lower side left open to permit the ingress of air. In the wall of said casing is formed a recess 9, which alines with and is adapted to receive the open end of the sleeve 3 when it is pushed 70 into the thimble 2.

In operation when it is desired to admit air into the car the sleeve 3 is pulled out to bring its head into contact with the vertical wall and segmental bearing of the casing 6, 75 thereby uncovering the lateral openings 5 and withdrawing its open end from the recess 9. Air then enters the lower open side of the casing 8, any dust or cinders carried thereby striking the upper closed side of the 80 casing, dropping by gravity back through the lower side thereof. From the interior of the casing 8 the air enters the open end of the sleeve 3 and flows therethrough and out through the lateral openings 5 into the casing 85 6, where it is deflected downward and out through the lower open side into the car.

Without limiting ourselves to the exact construction and arrangement of the parts shown and described, what is claimed is— 90

1. A ventilator comprising a longitudinally-movable sleeve having an open and a closed end and provided in its side near its closed end with radial openings, an open-sided casing inclosing one end of the sleeve, and 95 means extending beyond the casing through which the sleeve is operated, substantially as described.

2. The combination with a wall, window-sash, or the like having an opening through it, of a ventilator comprising a sleeve adapted to slide in the opening, and open-sided cas-

ings inclosing the opposite ends of the sleeve, substantially as described.

3. The combination with a wall, window-sash, or the like having an opening therein, 5 of a ventilator comprising a sleeve adapted to slide in said opening, and an open-sided casing inclosing one end of the sleeve and having a recess for reception of the end of the sleeve, substantially as described.
- 10 4. The combination with a window-sash having an opening extending through it, of means for controlling said opening, and a casing upon the exterior of the sash having a downwardly-opening side, said casing communicating with the opening in the sash, substantially as described.
- 15

5. The combination with a wall, window-sash, or the like having an opening therein, of a ventilator comprising a sleeve adapted to slide in said opening, and an open-sided 20 casing partially inclosing one end of the sleeve and provided upon its inner face with a bearing for the said end, substantially as described.

In testimony whereof we have signed our 25 names to this specification in the presence of two subscribing witnesses.

FRANZ BURGER.
HENRY M. WILLIAMS.
